UNITED STATES PATENT OFFICE.

BYRON A. BROOKS, OF BROOKLYN, NEW YORK.

PRINTING-TELEGRAPH.

SPECIFICATION forming part of Letters Patent No. 606,329, dated June 28, 1898.

Application filed January 20, 1894. Serial No. 497,553. (No model.)

To all whom it may concern:

Be it known that I, BYRON A. BROOKS, a citizen of the United States, residing in Brooklyn, in the county of Kings and State of New York, have invented certain new and useful Improvements in Printing-Telegraphs, of which the following is a specification.

My present invention consists in certain novel parts and combinations of parts forming a system of printing-telegraph and means for practically working such system and also certain novel methods. These novel features, both apparatus and methods, will be specifically pointed out in the claims concluding this specification.

The following is a description of the apparatus illustrated in the accompanying drawings and a few of the modifications thereof which may be adopted without departing from the spirit of my invention, broadly considered; but it will be understood that my invention is not limited to the precise parts and combinations of parts herein illustrated or to the modifications herein described.

Referring to the accompanying drawings, Figure 1 is a top view of a device located at the sending end of the line. Fig. 2 is a side view of the same. Fig. 3 is an end view of a device located at the receiving end of the line. Fig. 4 is a front view of the same. Fig. 5 is a top view of the same. Fig. 6 is an end view, and Fig. 7 a sectional view, of a distributor adapted to be used in combination with the other devices shown.

I will now describe the structure of the several devices shown in the drawings and the method of operating the same. This description will enable any one skilled in the art to employ my invention in the forms at present preferred by me.

Figs. 1 and 2 respectively show top and side views of a keyboard constructed on the general principle of a type-writer keyboard and also means for sending over a single line-wire electrical impulses, which at the receiving end of the line are caused to operate, through the medium of proper translating devices, a type-carrier. This sending apparatus may consist, as shown, of a keyboard merely, with proper connecting devices, or it may consist of a type-writer complete, the only difference being that in one case no printing will be done at the sending end of the line, while in the other printing will be simultaneously

performed at both the sending and receiving ends.

M, Figs. 1 and 2, is a shaft revolving at a determined speed by means of any suitable or convenient power. This shaft is arranged to constantly revolve at a determined speed. Instead of being so arranged it might be arranged to revolve at a determined speed for only a single revolution by means of a stoppin projecting into the path of a projection or depression on the shaft, (said pin being automatically withdrawn at each printing impulse,) or it might be arranged to work by the well-known step-by-step movement. 25 25 are a series of disks attached to said shaft, each carrying a pin c. The pins c on the several disks occupy different positions, being arranged progressively in the form of a spiral, so that only one of the pins is in a given line parallel to the axis of the shaft at any instant. At the forward end of the device is a series 75 of keys bearing one or more characters corresponding with the characters carried by the type-carrier operated thereby at the receiving end of the line. Besides the keys bearing characters there is a key marked 80 "Space," which has the function of an ordinary spacing-key in a type-writer, and the keys B and C, which control the position of the shifting platen, so as to print one or the other of the characters on the type-carrier 85 which are in a line at right angles to the line of print.

E is a scale, and D a pointer operating in connection therewith, so as to indicate the printing-point on the traveling platen at each 90 impulse, as in an ordinary type-writer. The frame carrying the pointer D is fed forward at each printing impulse for this purpose.

Now assuming that there is a shaft at the receiving end of the line revolving at precisely the same speed as is the shaft M or that there is at the receiving end some distributing mechanism always in the same phase of operation as is the shaft M, said shaft or mechanism being provided with means by 100 which at any given instant electrical contact or a cessation of electrical contact is made with controlling means for operating the type-carrier, it is plain that at this instant the impulse from the sending end of the line will 105 be delivered to said receiving mechanism and may be utilized to cause the type-carrier to print the corresponding character. It is also

- plain that if at successive points in the revolution of said shaft or simultaneously electrical contact is established with mechanism arranged to operate the several devices controlling the different elements of the type-carrier it is only necessary to provide at the sending end some means for closing or opening a circuit between the lines and the generator at that particular instant.
- 10 Key-levers 3 to 15, Fig. 1, are each pivoted on a bar 26, Fig. 2, and are bent upward, so as to stand behind an arm v' , pivoted at the lower end to the frame of the machine and carrying on the upper end a pivoted arm b .
- 15 The arm b carries a wedge-shaped pin c' , projecting from the side normally removed from the path of the pin c on its corresponding disk 25. When one of the said key-levers is depressed, it presses the bar v' forward until the projection c' is brought in the path of the pin c . When the pin c strikes the pin c' , (the surfaces of both being inclined,) it throws the bar v' still farther inward until it comes in contact with the contact-point g . The bar v'
- 20 being in circuit with a generator of electricity and the contact g being one of the terminals of the line-circuit when the pin f is brought in contact with the pin g the generator-current is transmitted over the line to the receiving end. In this way an electrical impulse is sent to line at a determined time--that is, at that instant during the revolution of the shaft M when the pin c on a given disk is passing the pin c' .
- 25 c'' is a pin also projecting from the side of the disk 25 behind the pin c , placed in such a position that when the pins f and g are in contact it will strike upon the other side of the pin c' and throw the rod v' back to its normal position, in which the pin c' is out of the path of the pin c .
- 30 h'' is a locking device which drops in position behind the tail of the rod b when it is pressed forward by the key-lever, so that having been pressed forward by the key-lever it will continue to stand in the path of the pin c until it is struck thereby. Without such or an equivalent device it is possible to conceive that the pin c' might be thrown in the path
- 35 of the pin c and be withdrawn therefrom before it had been struck thereby and that no electrical impulse would be sent over the line. This might readily occur if the key were depressed for an instant only just after the pin c had passed the contact-point.
- 40 Located at the receiving end of the line is a distributor. (Shown in Figs. 6 and 7.) It consists of a shaft J, made to revolve synchronously with the shaft M at the sending end. 28 is a disk mounted on said shaft J, carrying a wheel K, pivoted eccentrically thereto, the periphery of which extends above the periphery of wheel 28.
- 45 29 is a stationary drum provided with binding-posts corresponding in number with the key-levers at the sending end. Projecting

from the drum is a corresponding number of springs m and m' , insulated therefrom normally, but which are brought in electrical connection with each other at the instant that the wheel K passes under the contact-spring m . All the springs m' are constantly in electrical contact with the main-line wire through the binding-post 30. Whenever, therefore, a spring m' and the corresponding spring m are brought in contact, the current from the main line flows through binding-post 30, spring m' , spring m to the binding-posts 1 to 16, whichever is connected therewith. As each of these binding-posts is connected with the operating mechanism of one of the type-bars, the type-bar to which it is connected is caused to be thrown down to print.

Fig. 5 shows a series of magnets, numbered 3 to 15, each of which is connected with one of the printing type-bars. When a current is caused to pass through the coils of one of these magnets, its armature is attracted, which, being connected by the rod x in the ordinary way with a pivoted type-bar, throws it down against the platen.

By the above description it will be evident that in a structure organized as described the depression of a given key at the sending end will cause the corresponding key-lever to print at the receiving end, and that but a single line-wire is required to transmit the electrical impulses necessary to accomplish these results.

Referring to Figs. 3 and 4, G is the paper-carriage, capable of being vibrated so as to present the printing-point on the paper to either of the types on a type-bar. I have shown three types on a type-bar and a platen capable of being shifted from a central position both directions for the purpose above described. When the shift-key B, Fig. 1, is operated, the magnet 1, Fig. 3, causes the platen to vibrate by means of lever H, and when the shift-key C is operated the magnet 2 causes the platen to vibrate in the opposite direction by means of same lever H. The depression of either shift-key locks the platen in its new position by means of the lever N, Fig. 4, which under the influence of a spring slips behind the lever H. The platen is returned to its normal position by means of springs working against each other. (Not shown.)

The depression of either of the keys B or C, Fig. 2, raises automatically the lever 16 by the levers h h' , which are normally depressed by a spring. The release of either of these keys automatically depresses the lever 16, which thus sends a signal to its corresponding magnet 16, Fig. 4, which draws back the lever N and releases the lever H, which under the influence of its springs, as stated, returns the platen to its normal central position. It will thus be seen that the depression of either shift-key vibrates the platen of the receiver to the corresponding position and

holds it there until the proper character is printed, and when released it returns automatically to its normal position.

The central row of letters on the type-carrier, Fig. 1, is printed without the shift; but letters in either of the other rows are printed by first depressing the keys B or C.

I will now describe the method of transmission.

10 When a space between words is required, the key marked "Space" is depressed, which operates the type-bar 15, which has no type in the central position. The paper-carriage of the receiver is thereby fed forward a step 15 without printing.

The manipulation of the keys mechanically operates the space-pawl F, Fig. 1, which moves the pointer D over the scale E, which indicates the position of the printing-point on 20 the receiver. The pointer is fed against the spring N' and retained by the pawl F'. When the pointer D reaches the end of the scale, the pawl F' is automatically released by a projection on said pointer, and the pointer D 25 returns to the left under the influence of the spring N'. The pawl F may also be released by the magnet 17, operated by the return of the carriage in the receiver, and thus indicates the synchronism of the mechanism.

30 Referring to Figs. 3, 4, and 5, G is the frame of the paper-carriage, which travels longitudinally upon the rod I. O is the platen upon which the printing is done, over which the sheet of paper passes between the rolls Q Q'.

35 The T-shaped platen rests in the fork of the lever H, by which it is vibrated backward or forward. R is a rack attached to the carriage G, by which it is fed forward from right to left at each impression. This is effected by 40 the pawls r r', Fig. 5, operated by the local magnet L.

To each type-bar is attached a connecting-rod x, one end of which is connected to the armature of a magnet and the other to the 45 type-bar, near its fulerum. When the armature is drawn to the magnet, the rod x is impelled forward and the type-bar thrown down to print, a ribbon (not shown) being interposed between the type-bars and paper.

50 Each rod x is provided with two pins t t', which when the rod is thrown forward strike the lever l and makes connection with the local magnet L, by which the pawl r is operated to push the carriage one notch to the left against 55 the weight W, Fig. 4. The pawl r', Fig. 5, drops into the rack R and prevents its being drawn back until released. This is accomplished as follows: A sliding rod (not shown) is attached to the pawl r', which when the

60 carriage reaches its extreme movement to the left is struck by the end of the frame G, which throws the pawl r' out of the rack R. The carriage is then drawn back to the right by the weight W, when the rod is struck by the 65 other end of the frame G and the pawl r' is thrown into the rack R. Also, when the carriage G is drawn to the right the cam S, Figs.

4 and 5, strikes a projection on the frame of the printer and causes the rolls Q Q' to rotate sufficiently to feed the paper F forward to 70 present a new line for printing. These movements are all performed automatically when the end of the line is reached.

The operator perceives by the scale, Fig. 1, the position of the printing at the receiver, as 75 at each impression the pointer and the paper-carriage are each advanced one step. When the operator perceives that the printing is near the end of the line, he properly divides the word and then strikes the space-key one 80 or more times until the carriage reaches the limit of its motion, when it returns automatically. It will be observed that while the paper-carriage travels from right to left, as is necessary, the pointer travels from left to 85 right as the printing is done.

Having thus described the particular form of apparatus which is illustrated in the accompanying drawings and which is capable of performing the several functions desired, 90 I will incidentally point out some of the modifications which may be employed without departing from the spirit of my invention and without exceeding the scope of the concluding claims.

95 Instead of employing a plurality of type-bars each provided with a plurality of types characteristic of ordinary type-bar machines—as, for example, the Remington—which type-bars in the aggregate constitute 100 the type-carrier, I may employ any other suitable type-carrier—as, for example, a wheel with a plurality of rows of type at right angles to the line of print characteristic of the 105 class of type-writers known as "wheel-machines," of which the Hammond is a well-known example.

As far as the broad features of my invention are concerned it is immaterial whether the types in a plurality of rows at right angles to the line of print are carried on a single 110 type-carrier or on a plurality of independently-operating carriers, and it is immaterial whether the character itself approaches and is impressed upon the paper or whether the 115 paper approaches and makes contact with the type, and it is also immaterial whether the ink is applied to the type before impression or by a ribbon at the instant of impression. The term "type-carrier" in the claims is 120 therefore intended to include the feature broadly, independent of detail construction or mode of operation.

While, as I have stated, other forms of type-carriers may be used, I prefer to employ a 125 plurality of type-bars, as shown, since these enable the printing to be done in sight.

I have shown a type-carrier which has no movement in the lines of the several rows of type at right angles to the line of print that 130 it bears, the movement of the platen being relied upon to present the different rows of type to the printing-point; but I might employ a type-carrier either of the type-bar or

wheel variety which has an independent motion in this direction, or I might employ mechanism which shifts both the platen and the type-carrier in this direction, and thereby 5 still further reduce the number of operating-magnets with respect to the number of types which they operate. A shifting type-bar is now well known in the art.

The type-carrier, whether it be a wheel or 10 plurality of independently-moving type-bars, has on it a plurality of rows of type parallel with the line to be printed and a plurality of rows of type transverse to said line. By the shifting of the carrier or the platen, or both, 15 one or the other of the rows parallel with the line to be printed is brought into the position to be impressed.

I am aware that stock-telegraphs are old 20 in which a type-carrier is employed; but in 20 these the type-carrier is operated directly by mechanism at the sending end of the line, while in my system there is interposed between the type-carrier and the sending end a distributor which distributes the impulses, 25 whatever their character may be, to mechanism controlling the operations of the type-carrier.

I have shown one form of distributor, but 30 I do not wish to be understood as limiting myself to this form, as others might be used operating on substantially different principles. For example, the harmonic system of transmission and distribution might be employed.

35 I have described and shown rotating members at both ends of the line operating synchronously and continuously. Instead of using a continuously-revolving member I might employ members which revolve synchronously for only one complete revolution, 40 being stopped and started automatically by the impression of key-levers. This may be accomplished by providing the mechanism shown in the drawings with a pin withdrawn 45 mechanically at each impulse of the printing-key, allowing the shaft under the influence of a spring or other power to make one revolution, at the same time sending an impulse over the line-wire which will actuate a magnet, 50 causing it to withdraw simultaneously a corresponding pin from the distributor and allow it also to make one revolution.

It is obvious that while the shaft with its pins arranged spirally from left to right (see 55 Fig. 1) is making a revolution as many impulses may be sent successively in that order as keys are operated in the same order, or as many impulses may be sent successively as keys are actuated simultaneously in the order 60 in which the pins are placed on the revolving shaft. In view of this fact it is obvious that the shifting levers might be connected to and operated by the keys in the rows with which they are associated, because 65 when the rotating members make but a single complete revolution they would always be

stopped at the same point, and the first contact could be made to operate the shifting mechanism, which would continue in operation, as I have above described, until it was 70 released after the printing impulse. It is preferable to employ independently-operating shift-keys, as shown in the drawings, when capitals and small letters or other characters are to be printed by shifting the type-carrier 75 or the platen; but where the shifter is to be invariably used with a given row of keys I prefer to modify the mechanism, so that the shifting and printing operations are controlled by a single key. 80

In the mechanism described a current of electricity is caused to operate the controlling-magnet, but it will be understood that the action of the magnets might be reversed, so that the mechanism would be operated by the 85 interruption of the current.

Instead of using ordinary magnets to control the mechanism I may employ any other suitable apparatus—such, for example, as polarized relays. 90

It is obvious that connection may be made at each binding-post with two or more magnets, so that several operations may be performed simultaneously, if desired; also, that as many receivers as desired may be included 95 in the same circuit and operated simultaneously.

I have described the platen-carriage as positively fed forward by means of a magnet and returned to its initial position by a weight or a spring. If desired, it might be moved forward under the influence of a weight or spring and returned to its initial position by electrical means—for example, by a solenoid—or it might be fed in both directions by positive 100 electrical means.

While I have described the use of only one line-wire, a plurality of wires might be used, in number, however, less than the number of the characters on the type-carrier. 110

Some of the features herein described and claimed are applicable to electrical typewriters in which the sending and receiving elements are not located at a distance and in which there is, properly speaking, no line 115 wire or wires.

In the foregoing specification I have incidentally referred to some of the modifications which might be employed in the practice of my invention; but I have not endeavored to 120 specify all the modifications which might be adopted, the object of this specification being to instruct persons skilled in the art to which my invention relates to make and use the same in the form at present preferred by me 125 and to enable them to understand its nature, and I desire it to be distinctly understood that reference by me to some modifications is not in any way intended to exclude others not referred to, but which are within the spirit and 130 scope of my invention, and that in so far as my invention consists of novel methods these

are independent of the mechanism described or of any particular mechanism.

Many of the combinations and details illustrated and above described are not essential to the several features of my invention separately and broadly considered. All this will be indicated in the concluding claims, where the omission of an element or the omission of reference to the detail features of the elements mentioned is intended to be a formal declaration of the fact that the omitted elements or features are not essential to the inventions therein severally covered.

What I claim is—

1. In a printing-telegraph, a combined transmitter and distributor, comprising a continuously-revolving shaft, a set of key-levers, a circuit changer or changers and mechanism between the levers and shaft whereby the depression of any key changes the circuit to send an impulse over the line after a predetermined time corresponding to the key.

2. In a printing-telegraph, a combined transmitter and distributor comprising a uniformly-revolving shaft, a set of key-levers, a circuit changer or changers and mechanism between the levers and shaft whereby the depression of any key changes the circuit to send an impulse over the line after a predetermined time corresponding to the key, combined with a distributor at the receiving end revolving synchronously with the shaft and an electromechanical receiver.

3. In a printing-telegraph, a combined transmitter and distributor at the sending end, a keyboard, a line-wire, a distributor at the receiving end, an electromechanical receiver and mechanism combined with said keyboard whereby the depression of any key changes the circuit at a predetermined time corresponding to the revolution of the distributor and closes a local circuit corresponding to the key depressed on the keyboard.

4. In a printing-telegraph the combination of a keyboard at the sending end, a type-carrier at the receiving end having a plurality of rows of type, a plurality of magnets at the receiving end, means for distributing to the receiving-magnets the impulses transmitted by the operation of keys at the sending end, a longitudinally-traveling platen, a translating device and means for electrically energizing said translating device, whereby the platen and type-carrier have a relative vibratory motion to present one or the other of said rows in position to print by the operation of keys on the keyboard.

5. In a printing-telegraph, the combination of a keyboard at the sending end, a type-carrier at the receiving end having a plurality of rows of type, a longitudinally-traveling paper-carriage, a translating device, means for electrically energizing the said translating device, whereby the platen and type-carrier have a relative vibratory motion to present one or the other of said rows in position to print and means for causing the impres-

sion of the type, both the translating device and means for causing the impression of the types being controlled by the operation of 70 keys on the keyboard.

6. The combination of a keyboard, a type-bar carrying a plurality of rows of type, a vibrating and longitudinally-traveling platen and a translating device energized by a current of electricity whereby the platen is caused to vibrate transversely to the line of print by the operation of keys on the keyboard.

7. The combination of a type-carrier carrying a plurality of rows of type, a keyboard, a vibrating and longitudinally-traveling paper-carriage, translating devices controlled by a current of electricity by which the paper-carriage is caused to travel longitudinally and 85 to vibrate transversely to the line of print so as to impress any one of the type of the several rows.

8. The combination of a keyboard, a type-carrier having a plurality of rows of type, a 90 longitudinally-traveling platen, a translating device and means for electrically energizing said translating device whereby the platen and type-carrier have a relative vibratory motion to present one or the other of said rows in 95 position to print by the operation of keys on the keyboard and mechanism at the sending end whereby the shifted member is automatically returned to its normal position.

9. In a printing-telegraph, the combination 100 of a keyboard at the sending end, a type-carrier at the receiving end having a plurality of rows of type, a vibrating and longitudinally-traveling paper-carriage, a magnet by which the type-carrier is operated, a magnet by 105 which the platen is vibrated transversely to the line of print, and means for distributing to the respective magnets the impulses transmitted by the operation of corresponding keys on the keyboard.

10. The combination of a keyboard, a type-carrier carrying a plurality of rows of type, a vibrating and longitudinally-traveling paper-carriage, means energized by a current of electricity for moving said paper-carriage 115 longitudinally and vibrating it transversely to the line of print so as to impress any one of the types of the several rows and means for automatically returning it to its initial position.

11. In a printing-telegraph the combination 120 of a keyboard at the sending end, a type-carrier at the receiving end having a plurality of rows of type, a longitudinally-traveling paper-carriage, a translating device controlled 125 by a current of electricity whereby the platen and type-carrier have a relative vibratory motion to present one or the other of said rows of type in a plurality of new printing positions to print in a single line, means for holding the vibratory member in position and means for returning it to its normal position and for holding it there.

12. In an electromechanical printing mech-

- anism the combination of a keyboard containing character-keys and a shift-key with a series of type-carriers corresponding to the character-keys on the keyboard each provided with a plurality of types and a paper-carriage, said type-carriers and paper-carriage having a vibratory movement with relation to each other so as to print the several types in line, a source of electrical energy and means controlled by the operation of said shift-key whereby the shifted member is automatically locked when the shift-key is depressed and unlocked when said key is released.
13. In a printing-telegraph, key-levers and a revolving shaft provided with contact-points at the sending end, combined with a distributor composed of a synchronously-revolving arm, and suitable contact-points, a type-carrier carrying a plurality of rows of types, a paper-carriage, said carriage and carrier having a vibratory movement in relation to each other and electrotranslating devices by means of which they are operated at the receiving end.
14. In a printing-telegraph, the combination of a keyboard at the sending end containing character-keys and a shift-key with a plurality of type-carriers at the receiving end each provided with a plurality of types and a paper-carriage said type-carriers and paper-carriage having a vibratory movement with relation to each other, a line-wire and means controlled by said shift-key whereby the paper-carriers are shifted to receive the impression of the several types on the type-carriers, an automatic lock for locking the shifted member and mechanism at the sending end whereby an impulse is sent over the line to unlock said member and allow it to return to its normal position.
15. In a printing-telegraph the combination of a keyboard containing character-keys and shift-keys, means for sending a succession of impulses over a line-wire by the operation of said keys, an electromechanical printing mechanism comprising a plurality of type-carriers each provided with a plurality of rows of type and a paper-carriage, said carriage and type-carriers having a vibratory movement with relation to each other controlled by the operation of shift-keys on the keyboard.
16. The combination with a keyboard of a scale and pointer, means for causing said pointer to advance at each printing impulse by the operation of the printing mechanism, a magnet for releasing said pointer and means for automatically returning it to its initial position.
17. In a printing-telegraph, a keyboard, a uniformly-revolving shaft, a circuit changer or changers at the sending end combined with a synchronously-revolving shaft at the receiving end, local circuits corresponding to keys and electromechanical printing mechanism comprising a plurality of type-carriers each provided with a plurality of rows of type

and a paper-carriage, said carriage and carriers having a vibratory movement with relation to each other controlled by a current of electricity.

18. The combination of a keyboard, a type-carrier having a plurality of rows of types, a platen, said platen and type-carrier having a vibratory motion with relation to each other and an electromagnet by which said vibration is caused, mechanical means for retaining the vibrating member in position during the operation of printing and means for releasing said vibrating member and returning it to its normal position.

19. The combination with a type-carrier provided with a plurality of rows of type, a keyboard, a vibrating and longitudinally-traveling platen, a translating device energized by a current of electricity whereby the platen is vibrated to a plurality of new printing positions so as to impress any one of the types of the several rows by the operation of keys on the keyboard, means for holding it in its new printing position and means for returning it to its normal position.

20. The combination of a keyboard, a type-carrier provided with a plurality of rows of type, a vibrating and longitudinally-traveling platen, a translating device energized by a current of electricity whereby the platen is vibrated to a plurality of new printing positions by the operation of keys on the keyboard, means for holding it in its new printing position and means for automatically returning it to its normal position and for holding it there.

21. The combination of a keyboard, a plurality of type-carriers each provided with a plurality of type, a longitudinally-traveling paper-carriage, means controlled by a current of electricity by which the paper-carriage is vibrated from a normal printing position to a plurality of new printing positions, mechanical means for retaining it in position during the operation of printing and means for returning it to its normal printing position and for holding it there.

22. In a printing-telegraph the combination of an electromechanical printing mechanism comprising a plurality of type-carriers each provided with a plurality of rows of type and a paper-carriage, said carriage and type-carriers having a vibratory movement with relation to each other, a keyboard at the sending end comprising character-keys and shift-keys and means whereby when a shift-key is operated a vibratory movement is effected in the printing mechanism between said type-carriers and paper-carriage, means for retaining said vibratory member in its shifted position until printing is effected and means for automatically restoring it to its normal position.
